BOTTLE-STERILIZING ARRANGEMENT

Oliver H. Brewster, Essex Fells, N. J., assignor to
Electrical Industries, Inc., Newark, N. J., a corporation of New Jersey

Application December 3, 1946, Serial No. 713,693

7 Claims. (Cl. 21—79)

1

The present invention relates to bottle-supporting arrangements and, particularly, to such arrangements as employed in bottle sterilizers of the type useful in sterilizing infants' nursing bottles.

In applicant's copending application Serial No. 639,259, filed January 5, 1946, entitled "Sterilizing device," and assigned to the same assignee as the present application, there is disclosed a bottle sterilizer of the type mentioned and having a hollow base member in which steam is generated. The base member is provided with spaced jets through which the steam is directed to the interior of bottles to be sterilized. The bottles are supported over the steam jets by a plurality of wire loops which are secured to a flange member supported by a pedestal in spaced relation to the base member. This bottle-supporting arrangement is relatively expensive to fabricate, requires a heavier base construction than is desirable, and does not possess a sturdiness comparable with the rest of the sterilizer.

It is an object of the present invention, therefore, to provide in a bottle sterilizer a bottle-supporting arrangement having a sturdy yet relatively inexpensive construction.

It is a further object of the invention to provide in a bottle sterilizer a bottle-supporting arrangement which may be fabricated in part from sheet material, for example sheet metal, thereby permitting a wide choice in the selection of the material used particularly with regard to certain important qualities thereof such as, rigidity, strength, ease of fabrication, corrosion resistance, and the like.

In accordance with a particular form of the invention, there is provided in a bottle sterilizer, a bottle-supporting arrangement comprising: a sterilizer base member including a plurality of spaced vapor jets integrally formed therewith and protruding therefrom and each adapted to receive the mouth of an individual bottle to be sterilized, each of the jets having an effective transverse dimension substantially equal to the internal diameter of the bottle mouth to restrain the bottle against substantial movement at the region of the mouth thereof but having at least one circumferential groove longitudinally thereof to permit drainage of vapor condensate out of the bottle; and an apertured plate member secured to the base member in spaced relation therewith and with the apertures thereof corresponding in number to the vapor jets and arranged in alignment therewith to support individual ones of the bottles at a circumferential re-

gion thereof spaced from the vapor jets, whereby each of the bottles is supported on the base for sterilization only by an individual one of the jets and the plate member.

For a better understanding of the present invention, together with other and further objects thereof, reference is had to the following description taken in connection with the accompanying drawing, and its scope will be pointed out in the appended claims.

Referring now to the single figure of the drawing, there is shown a bottle sterilizer particularly useful for sterilizing infants' nursing bottles. The sterilizer includes a bottle-supporting arrangement embodying the present invention and comprising a base member 10 of dish-shaped configuration having a centrally disposed well 11 in which are positioned a pair of spaced electrodes 12, 13 of compressed carbon or the like. The electrodes 12, 13 are connected by conductive members, which extend through sealed holes in the bottom of the base member 10, to individual conductors of an electrical power-supply cord 14.

The base member includes a cover 15 which is secured to the base member by spaced machine screws 16 to form therewith a chamber closed except for a very slight spacing between the periphery of the cover 15 and the base member 10.

The cover 15 includes a plurality of protruding spaced vapor jets 17 extending normal to a plane which includes the approximately flat upper surface of the cover, each of the jets 17 being adapted to receive, or be received within, the mouth of an individual bottle to be sterilized to restrain the bottle against substantial movement at the region of the mouth thereof. The jets 17 project from the cover 15 with approximately triangular cross section and have a centrally disposed orifice communicating with the steam chamber formed between the base member 10 and its cover 15.

The bottle-supporting arrangement also includes an apertured plate member 18 of relatively rigid sheet metal, for example aluminum, supported by and in spaced relation to the cover 15 with the apertures 19 of the plate member corresponding in number to the vapor jets 17 and arranged in alignment therewith to support individual ones of the bottles at a circumferential region thereof spaced from the vapor jets. In particular, a plurality of spaced pedestals 20 are suitably secured to the cover 15 and the plate member 18 is secured to the pedestals 20 by machine screws 21. Infants' nursing bottles usually have a cylindrical body terminating at one end in a shoulder from which a relatively small neck ex-

tends to the mouth portion. The apertures 19 of the plate member 18 may engage the cylindrical body portion of such bottles at a region well spaced from the mouth thereof. Preferably, however, each aperture 19 is smaller than the diameter of the body of the bottle so that the shoulder of the bottle rests upon the periphery of the aperture to support the bottle with the mouth thereof engaging one of the jets 17 but out of engagement with the cover 15 of the base member.

The sterilizer includes a cover 22 which fits within the raised lip of the base member 10 to enclose the bottles to be sterilized.

Considering now the operation of the sterilizer just described, a small quantity of water is poured into the base member 10 and flows through the small gap between the base member and its cover 15 to the well 11 partially to immerse the electrodes 12 and 13. Electrical current flowing between the electrodes heats the water to the boiling point to generate steam. The steam flows out of the jets 17 and is directed by the latter to the interior of the bottles to be sterilized. A portion of the steam flows, with the condensate, out of the mouth of the bottle and fills the entire chamber within the cover 22 to sterilize the exteriors of the bottles together with any other implements which may be enclosed with the bottles for sterilization. It is to facilitate such escape of steam from the interior of the bottles, and also to permit condensate to return to the well 11, that the vapor jets 17 have the triangular cross section previously mentioned and the mouth of each bottle is maintained out of engagement with the cover 15 by the use of apertures 19 of suitable size to support the bottle by engagement with its shoulder. Any condensate which returns to the well 11 is used again, the sterilizing process continuing until there is sufficient loss of steam around the lip of the cover 22 to the exterior atmosphere that all of the water is exhausted. This may require some 15 or 20 minutes, depending upon the quantity of water originally used.

The bottle-supporting arrangement is a sturdy yet simple and relatively inexpensive one, particularly in that the jets 17 are easily moulded integrally with the cover 15 of the base member and the apertured plate member 18 may simply be die-stamped from sheet material. Further, the supporting pedestals 20 are preferably moulded into the cover 15 and may be sufficiently well spaced from each other that there is little danger of breakage of the cover 15 should the plate member 18 receive a sharp blow. These features enable the bottle sterilizer to be fabricated as a compact, sturdy unit involving only a simple and relatively inexpensive construction.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. In a bottle sterilizer, a bottle-supporting arrangement comprising: a sterilizer base member including a plurality of spaced vapor jets integrally formed therewith and protruding therefrom and each adapted to receive the mouth of an individual bottle to be sterilized, each of said jets having an effective transverse dimension substantially equal to the internal diameter of said

bottle mouth to restrain said bottle against substantial movement at the region of the mouth thereof but having at least one circumferential groove longitudinally thereof to permit drainage of vapor condensate out of said bottle; and an apertured plate member secured to said base member in spaced relation therewith and with the apertures thereof corresponding in number to said vapor jets and arranged in alignment therewith to support individual ones of said bottles at a circumferential region thereof spaced from said vapor jets, whereby each of said bottles is supported on said base for sterilization only by an individual one of said jets and said plate member.

2. In a bottle sterilizer, a bottle-supporting arrangement comprising: a sterilizer base member having an approximately planar surface from which protrude approximately normal thereto a plurality of spaced vapor jets integrally formed therewith and each adapted to receive the mouth of an individual bottle to be sterilized, each of said jets having an effective transverse dimension substantially equal to the internal diameter of said bottle mouth to restrain said bottle against substantial movement at the region of the mouth thereof but having at least one circumferential groove longitudinally thereof to permit drainage of vapor condensate out of said bottle; and an apertured plate member secured to said base member in spaced relation therewith and with the apertures thereof corresponding in number to said vapor jets and arranged in alignment therewith to support individual ones of said bottles at a circumferential region thereof spaced from said vapor jets, whereby each of said bottles is supported on said base for sterilization only by an individual one of said jets and said plate member.

3. In a bottle sterilizer, a bottle-supporting arrangement comprising: a sterilizer base member including a plurality of spaced vapor jets integrally formed therewith and protruding therefrom approximately normal to a common plane and each adapted to receive the mouth of an individual bottle to be sterilized, each of said jets having an effective transverse dimension substantially equal to the internal diameter of said bottle mouth to restrain said bottle against substantial movement at the region of the mouth thereof but having at least one circumferential groove longitudinally thereof to permit drainage of vapor condensate out of said bottle; and an apertured plate member secured to said base member in spaced relation therewith and with the apertures thereof corresponding in number to said vapor jets and arranged in alignment therewith to support individual ones of said bottles at a circumferential region thereof spaced from said vapor jets, whereby each of said bottles is supported on said base for sterilization only by an individual one of said jets and said plate member.

4. In a bottle sterilizer, a bottle-supporting arrangement comprising: a sterilizer base member including a plurality of spaced vapor jets integrally formed therewith and protruding therefrom and each adapted to be received within the mouth of an individual bottle to be sterilized, each of said jets having an effective transverse dimension substantially equal to the internal diameter of said bottle mouth to restrain said bottle against substantial movement at the mouth thereof but having at least one circumferential groove longitudinally thereof to permit drainage of vapor condensate out of said bottle; and an apertured plate member secured to said base member in spaced relation therewith and with the apertures

thereof corresponding in number to said vapor jets and arranged in alignment therewith to support individual ones of said bottles at a circumferential region thereof spaced from said vapor jets, whereby each of said bottles is supported on said base for sterilization only by an individual one of said jets and said plate member.

5. In a bottle sterilizer, a bottle-supporting arrangement comprising: a sterilizer base member including a plurality of spaced vapor jets integrally formed therewith and protruding therefrom and each adapted to receive the mouth of an individual bottle to be sterilized, each of said jets having an effective transverse dimension substantially equal to the internal diameter of said bottle mouth to restrain said bottle against substantial movement at the region of the mouth thereof but having at least one circumferential groove longitudinally thereof to permit drainage of vapor condensate out of said bottle; and an apertured plate member of relatively rigid sheet material secured to said base member in spaced relation therewith and with the apertures thereof corresponding in number to said vapor jets and arranged in alignment therewith to support individual ones of said bottles at a circumferential region thereof spaced from said vapor jets, whereby each of said bottles is supported on said base for sterilization only by an individual one of said jets and said plate member.

6. In a bottle sterilizer, a bottle-supporting arrangement comprising: a sterilizer base member including a plurality of spaced vapor jets integrally formed therewith and protruding therefrom and each adapted to receive the mouth of an individual bottle to be sterilized, each of said jets having an effective transverse dimension substantially equal to the internal diameter of said bottle mouth to restrain said bottle against substantial movement at the region of the mouth thereof but having at least one circumferential groove longitudinally thereof to permit drainage of vapor condensate out of said bottle; and an apertured plate member of relatively rigid sheet

metal secured to said base member in spaced relation therewith and with the apertures thereof corresponding in number to said vapor jets and arranged in alignment therewith to support individual ones of said bottles at a circumferential region thereof spaced from said vapor jets, whereby each of said bottles is supported on said base for sterilization only by an individual one of said jets and said plate member.

10 7. In a bottle sterilizer, a bottle-supporting arrangement comprising: a sterilizer base member including a plurality of spaced vapor jets integrally formed therewith and protruding therefrom and each adapted to receive the mouth of an individual shouldered bottle to be sterilized, each of said jets having an effective transverse dimension substantially equal to the internal diameter of said bottle mouth to restrain said bottle against substantial movement at the region of the mouth thereof but having at least one circumferential groove longitudinally thereof to permit drainage of vapor condensate out of said bottle; and an apertured plate member secured to said base member in spaced relation therewith and with the apertures thereof corresponding in number to said vapor jets and arranged in alignment therewith to support individual ones of said bottles by engagement with the shoulder thereof while maintaining the mouth of said bottle out of engagement with said base member, whereby each of said bottles is supported on said base for sterilization only by an individual one of said jets and said plate member.
